UNITED STATES PATENT OFFICE.

FREDERICK B. FRANKS, OF BATH, PENNSYLVANIA.

PULVERIZER.

1,204,385.

specification of Letters Patent. Patented Nov. 7, 1916.

Application filed July 20, 1916. Serial No. 110,344.

To all whom it may concern:

Be it known that I, FREDERICK B. FRANKS, a citizen of the United States, and a resident of Bath, county of Northampton, State of Pennsylvania, have invented certain improvements in Pulverizers, of which the following is a specification.

My invention relates to certain improvements in pulverizers used for grinding cement, phosphate, coal, ore, or other materials.

One object of the invention is to increase the capacity of a pulverizer of the type which I will proceed to describe and to allow the fine particles to pass immediately to the screen as they enter the pulverizer. This object I attain by dispensing with the deep sheet metal ring usually employed and I also dispense with the hopper for directing the material into the space inclosed by said ring.

A further object of the invention is to reduce the number of separate parts in the yoke by making the yoke and the means for supporting the blades of an integral structure.

In the accompanying drawings: Figure 1 is a sectional elevation on the line 1-1, Fig. 2, illustrating my invention; Fig. 3 is a sectional plan view on the line 2-2, Fig. 1; Fig. 3 is a detached perspective view of the yoke showing the blades secured thereto but the pushers removed therefrom; and Fig. 4 is a view of my improved yoke having an integral narrow bracing ring at the top.

Referring to the drawings, 1 is the grinding ring mounted in an intermediate section 2 supported by a lower section 3. Located upon the intermediate section is an upper section 4 in which the screen 8 is mounted. This is the general mechanism of a standard pulverizer.

10 is a vertical shaft adapted to suitable bearings 11 in the frame of the machine. 45 This shaft is driven by power and mounted on the shaft, in the present instance, is a belt pulley 12. Secured to the shaft is a yoke 5 having four arms 6 carrying the pushers 7 and mounted between the pushers are the 50 crushing balls 9 which travel in the grooved face of the grinding ring 1. The yoke, in the present instance, is mounted in a support 13 carried by the shaft, but any suitable arrangement may be provided for securing 55 the yoke to the shaft.

14 is a cap plate on which is mounted a

feed trough 16 having a discharge opening which communicates with the interior of the pulverizer, preferably near the center thereof. The material is fed through this trough by any suitable mechanism and is discharged into the upper section of the pulverizer and as soon as the material passes into the machine the fine particles are thrown out toward the screen by centrifugal force due to the rotation of the yoke, carrying blades which are hereinafter described. The very fine particles pass through the screen 8, while the coarser particles work down into the space between the balls and the grinding ring 1 and are pulverized by the action of the balls. The fine particles formed by the crushing action are drawn up and are thrown against the screen by centrifugal force, while the coarser particles are reground to the proper degree of fineness, after which they also pass through the screen.

Heretofore, it has been the practice to secure a deep sheet metal ring to the yoke by rivets and to fasten a number of fan brackets to the ring, also by rivets. A hopper is usually secured to the cap plate and extended into the space within the ring so that the material did not escape until it reached the lower portion of the compartment inclosed by the yoke hub. This construction was objectionable, mainly because it impeded the free movement of the fine particles of material to the screen, thus considerably reducing the capacity of the machine. Furthermore, by making the yoke member of a number of parts riveted together, the rivets, owing to the excessive strain to which the yoke was subjected, would become loose and the ring, and its parts, would rattle and would eventually break away from the yoke structure, due to the centrifugal action and to the high speed at which the yoke travels.

By my invention, I dispense entirely with the sheet metal parts and the rivets for securing the parts to the yoke by forming an integral annular flange 21 on the upper portion of the yoke and by forming diagonal, integral brackets 22, which project from this flange to which the inclined blades 23 are secured by means of bolts 24. I also provide integral arms 25 which project from the upper surface of the flange 21. On these arms are brackets 26 to which are secured the vertical blades 27 by bolts 28. In order

to reinforce these brackets, particularly on the larger machines, I provide inclined braces 29, which extend from the arms to the hub portion of the yoke, as clearly shown in Fig. 1. The arms rigidly support the vertical blades and the brackets 22 rigidly support the diagonal blades, making an exceedingly substantial yoke structure which is not likely to be broken as it is preferably made of high grade material and there are no loose parts, other than the bolts which retain the blades to the arms so that the liability of the parts becoming loose and breaking the other elements of the machine is obviated to a great extent.

In machines of this type the yoke travels 1000 ft. per minute and formerly when anything broke it was necessary to shut down the mill so that the parts could be taken out and repaired. By my invention the fan center is dispensed with and the blade supports, as well as the arms of the pusher, are made integral with the yoke. Furthermore, the fan blades can be readily removed and replaced without dismantling the mill as formerly, and the parts can be made much cheaper than when manufactured prior to my invention.

In some instances, and particularly in machines of the larger sizes, it may be necessary to connect the upper portions of the vertical arms 25 and this can be done by the use of a narrow connecting ring 30, as illustrated in Fig. 4, which extends from the upper end of one vertical arm to another and in this case the diagonal strengthening ribs 29 may be dispensed with or used in connection with the ring. The ring is very narrow and is preferably of such a shape in cross section that it will not interfere with the free passage of the material to the screen as it will be understood that a certain portion, possibly from 15 to 20% of the material, is of such a fineness as to pass freely to the screen without being ground between the ring and the balls.

The operation of the machine is as follows: The material to be pulverized is fed into the upper portion of the machine by any suitable feed apparatus, such as shown at 16, and flows directly into the chamber inclosed by the screen. The shaft carrying the yoke on which the blades are mounted travels at a very high speed and, consequently, any material discharged into the machine will immediately be thrown against the screen by the centrifugal action of the blades. The finer particles of the material, possibly 15 to 20%, are fine enough to pass directly through the screen without being subjected to the action of the balls, while the coarser particles pass down into the space inclosed by the ring and are subjected to the grinding action and, as the particles are broken, the finer particles are carried by

centrifugal force and whirled against the screen, while the very fine particles pass therethrough. This process is carried on until all of the material is reduced to a powder. The diagonal blades are for the purpose of lifting the powdered material as it is formed and the blades 27 catch the powdered material and direct it against the screen. By dispensing with the hopper and the usual wide ring carried by the yoke the output of the mill is greatly increased.

As an instance, the difference between the area of the openings in the old style pulverizer using the wide fan center and the present one in which integral arms are used and in which the fan center is dispensed with is, in a 42" mill, as follows: In a mill using the fan center, the area of opening is about 270 sq. ins., whereas the area of opening in a mill in which the fan center is dispensed with is about 722 sq. ins. Furthermore, I find by practical experiments that the repairs and labor to operate my improved mill are very much less than the repairs and labor in a mill having the sheet metal fan center and the hopper.

While I have shown one type of pusher, it will be understood that any suitable pusher may be used without departing from the main features of the invention.

I claim:

1. The combination in a pulverizer, of a frame; a screen; a fixed grinding ring; a driven shaft; a yoke carried by the shaft; grinding balls arranged to be driven by the yoke and to travel in contact with the ring; vertically extending arms projecting upwardly from the yoke; and fans secured to the said arms, the space between the arms being open for the free passage of the material to the screen.

2. The combination in a pulverizer, of a frame; an annular screen; a fixed grinding ring below the screen; a driven shaft; a yoke carried by the said shaft; balls propelled over the grinding ring by the yoke; upwardly projecting arms; fan blades secured to the arms, the space between the arms being entirely open and the upper portion of the pulverizer inclosed by the screen being free of obstructions with the exception of the arms of the yoke so that as the material enters the pulverizer the fine particles will be carried immediately to the screen by the centrifugal action of the blades.

3. The combination in a pulverizer, of a frame; an annular screen; a fixed grinding ring; a driven shaft; a yoke carried by the said shaft, said yoke having integral arms; pushers mounted on the arms; balls propelled over the grinding ring by the pushers and arranged to travel in contact with the ring; integral brackets projecting from the yoke; and fans secured to the brackets.

4. The combination in a pulverizer, of a

frame; an annular screen; a grinding ring mounted on the frame; a vertical shaft; a yoke carried by the shaft having integral arms; pushers secured to the arms; balls mounted in advance of the pushers and arranged to travel against the grinding ring, said yoke having a series of integral vertical arms provided with brackets; a series of integral inclined brackets; and fan blades secured to both sets of brackets.

5. A yoke for a pulverizer made as an integral structure and having integral vertical arms and inclined brackets to which the

fan blades are secured, the space between the vertical arms being open for the free passage of the material.

6. A yoke for a pulverizer made of a single casting having integral, radial pusher arms projecting from the lower portion thereof and reinforced vertical arms carrying brackets to which the fan blades are secured; and a series of integral diagonal brackets to which the diagonal blades are secured, said yoke having a hub arranged to be secured to a power driven shaft.

FREDERICK B. FRANKS.
